Specification for Design.

Patented Apr. 23, 1912.

Application filed September 25, 1911. Serial No. 651,298. Term of patent 14 years.

To all whom it may concern:

Be it known that I, WALTER E. TRAUTWEIN, a citizen of the United States, residing at Fort Wayne, in the county of Allen and State of Indiana, have invented a new, original, and ornamental Design for Display-Boards, of which the following is a specification, reference being had to the accompanying drawing, forming part thereof.

The figure is a perspective view of a display board, showing my new design.

The display board presents a spaced front and is inclosed by a rectangular casing which has at its upper end two miniature cases, oppositely disposed and each presenting a glazed face in its side nearest the side of the case proper and at right angles to the spaced front of the board.

I claim:

The ornamental design for a display board, as shown and described.

WALTER E. TRAUTWEIN.
